FIG. 1

FIG. 2

FIG. 3

FIG. 4

FIG. 5

FIG. 1 is a front perspective view of a combined telephone handset and desk stand showing my new design;

FIG. 2 is a rear corner perspective view, to a reduced scale, of a combined telephone handset and desk stand shown in FIG. 1;

FIG. 3 is a left end elevational view of a combined telephone handset and desk stand shown in FIG. 2;

FIG. 4 is a right end elevational view of a combined telephone handset and desk stand shown in FIG. 2; and

FIG. 5 is a side elevational view of a combined telephone handset and desk stand shown in FIG. 2.

The dominant features of my new design reside in the portions shown in full lines on the drawing.

I claim:

The ornamental design for a combined telephone handset and desk stand, substantially as shown and described.
